UNITED STATES PATENT OFFICE.

JEROME E. BAUM, OF NEW YORK, N. Y.

DESIGN FOR A TOILET-ACCESSORY CONTAINER.

Application filed December 24, 1928. Serial No. 29,402. Term of patent 7 years.

To all whom it may concern:

Be it known that I, JEROME E. BAUM, a citizen of the United States, residing at New York city, county of New York, borough of Manhattan, and State of New York, have invented a new, original, and ornamental Design for Toilet-Accessory Containers, of which the following is a specification, reference being had to the accompanying drawing, forming a part thereof.

I claim:

The ornamental design for a toilet accessory container, as shown.

JEROME E. BAUM.
